UNITED STATES PATENT OFFICE.

HENRY PETERSEN, OF MOUNT AUBURN, IOWA.

CULTIVATOR.

1,161,964.

Specification of Letters Patent. Patented Nov. 30, 1915.

Application filed February 20, 1914. Serial No. 819,956.

To all whom it may concern:

Be it known that I, HENRY PETERSEN, a citizen of the United States of America, and resident of Mount Auburn, in the county of Benton and State of Iowa, have invented certain new and useful Improvements in Cultivators, of which the following is a specification.

This invention relates to certain new and useful improvements in cultivators and is designed more especially as an improvement upon the construction shown in my patent #1,084,291, issued January 13, 1914.

The present invention has for its objects among others to provide a simplified construction, to cheapen the manufacture and to dispense with parts shown in connection with the mast in my prior patent, thus employing fewer parts requiring less material and enabling me to manufacture the device much easier than heretofore.

I abandon the mast stop cushioning spring of the prior patent and also the mast stop acting in conjunction with said cushioning spring and provide the toothed segment with a projection which serves as a mast stop, being so disposed as to act upon the main spring which tensions the mast. As the mast is thrown rearward, this projection or toe is brought upward against the spring to be put under tension, thus not only causing the mast to come to a stop, but serving also as a cushion therefor. The parts are so arranged that the effect of the projection or toe on the spring is gradually applied.

Other objects and advantages of the invention will hereinafter appear and the novel features thereof will be particularly pointed out in the appended claims.

The invention is capable of embodiment in a variety of forms, some only of which I have chosen to herein illustrate. The invention as embodied in such forms is clearly illustrated in the accompanying drawings, which, with the numerals of reference marked thereon, form a part of this specification, and in which—

Figure 1 is a side elevation showing my improvement as applied to a cultivator, such portions only of the latter as are necessary to a clear understanding of my present improvements being shown. Fig. 2 is a similar view with the parts in the position they assume when the mast and main lever are

thrown forward. Fig. 3 is a perspective view of the mast in one of its embodiments. Fig. 4 is a similar view of a modified form. Fig. 5 is a perspective view of still another form of the invention. Fig. 6 is a front elevation on a smaller scale of the form shown in Fig. 3.

Like numerals of reference indicate like parts throughout the several views.

Referring to the drawings, 1 designates the main frame, 2 the crank axle, 3 the gang frame, 4 the pendulum bar, and 5 the main operating lever, all of which, together with the other parts of the implement, may be of the form shown in my prior patent above referred to, or of any other well known or approved form of construction, the present improvement residing solely in the mast and its appurtenances.

As before stated, the present improvement is capable of embodiment in a variety of forms and upon reference to Fig. 3 there will be seen a mast 6 which is mounted in the present instance upon a cross bar 7 connecting the side bars of the frame, the pivot 8 of said mast being above and substantially in alignment vertically with the axle. This pivot 8 is mounted in the ears 9 on a casting or bracket 10 secured to said cross bar, or it may be mounted in any other convenient way. The lower end of the mast is bifurcated, as seen in Fig. 3, the bifurcations 11 receiving the pivot and being disposed adjacent to the ears 9 so as to prevent lateral movement or undue swinging of the mast in a direction parallel with the pivot.

12 is a spring actuated pawl carried by the rod 13 and designed to be operated by the lever 14 which is mounted at the upper end of the mast, as shown. This pawl is designed for coöperation with a toothed segment 15 mounted upon the pivot 8 and provided with lateral projections or lugs 16 and 17 to limit the mast in its backward and forward movements. It is to be understood that the mast and segment are locked by means of this pawl so as to move together as one in moving the gangs up or down. If it be desired to change the depth of penetration of the earth-engaging implements into the ground, the pawl is disengaged from the segment and the segment adjusted or moved on its pivot in one direction or the other, according to whether it is desired to raise or lower the gangs, and the pawl then

engaged in the appropriate notch in the segment, when the mast and segment will again move together.

18 is a spring disposed about the pivot 8 and having a portion 19 acting on the lower portion of the geared segment, as seen clearly in Fig. 3 and also in Fig. 6, serving to throw the segment in the direction of the arrow in Fig. 3, when the pawl 12 is out of engagement with the said segment, so as to move the segment into the desired position of the mast for the engagement of the pawl at the proper point of the segment in accordance with the desired depth of penetration of the earth-engaging elements.

20 20 is a spring for carrying the weight of the gang and the mast and for holding the mast in position with the gang raised. It is to be understood that this spring is at all times under tension, the tension of the spring, however, being varied, that is increased when the mast is thrown rearward. This spring is attached at one end, as at 21, in any suitable manner to the main frame 1 and its other end is designed to act upon the mast. The mode of connection of this other end of the spring varies in accordance with the different forms of embodiment of the invention. For instance, in Fig. 3 I have shown a clevis 22 pivotally mounted, as at 23, to the opposite sides of the mast and in this instance the rear end of the spring is connected, as at 24, with the forward end of the cross bar of this clevis. 25 This clevis extends forward a sufficient distance to permit of the necessary movements of the toothed segment, which, as will be seen, is disposed within the bifurcation of the lower end of the mast. In this form the forward end of the clevis is provided with a projection 25 designed to engage the under side of the spring, as seen in said Fig. 3, providing a long bearing for the spring, this projection having its upper surface convex to lessen the suddenness of application of tension to the spring and to prevent injury to the spring by increasing the points of bearing or support of the spring on said projection. In this form the toothed segment is provided with a forward projection 26, which, when the mast is moved rearward, contacts with the under side of the projection 25 to force the same up into engagement with the spring.

50 55 With the parts constructed and arranged substantially as hereinbefore described, the operation, which, it is thought, will be clearly understood, is briefly stated, as follows.

60 65 Assuming the parts to be in the position in which they are shown in Fig. 2, the gangs raised and the projection 25 out of engagement with the spring, and the pawl 12 in proper engagement with the segment, now as the mast is moved rearward into the posi-

tion indicated in Fig. 1, the segment and mast move together and the projection 26 on the segment engaging the projection 25 on the clevis causes the latter to be brought into engagement with the under side of the 70 spring 20, thus putting the same under greater tension, and thus serving as a cushion stop for the mast.

Referring now to Fig. 4, I have shown a double toothed segment 27 mounted upon 75 the pivot 8 in the ears 9 on the cross bar 7, the mast 6 being provided with a lever 14 adapted to actuate the spring pawl 12 by means of the connecting rod 13, the same as in Fig. 3 with the exception that the pawl 80 has a double extension 28 so as to engage in the notches of both sides of the toothed segment, it being noted that the mast is movable between said side bars and is limited in one direction by the cross portion 29 which connects said side bars at the rear and in the other direction by the lug or the like 85 30 projecting inwardly from the side of the segment. In this form the spring 20 is connected to the clevis 31 pivotally mounted 90 upon the mast, as at 32. In this form the toothed segment is provided with a forwardly projecting lip 33 which extends beyond the clevis and engages the under side of the spring to put the same under tension 95 when the mast is thrown rearward. The upper face of this lip is convex for the same purpose as the convexity of the projection 25 on the clevis in the form shown in Fig. 3. In this form a spring 34 is provided about the pivot 8 and acting upon the toothed segment in the same manner as the spring 18 in the form shown in Fig. 3, except in this form the cross portion 35 of the spring bears against the rear face of the 100 mast instead of upon the front face of the toothed segment. The operation, however, is substantially the same as with the form 105 shown in Fig. 3 and above described.

In Fig. 5 I have shown another form in 110 which the single toothed segment 36 is pivotally mounted upon the pivot 8 in the same manner as before, except that it is reversed as to position, that is its free end extends from the rear forwardly instead of from the 115 front rearwardly, as in Fig. 3. The mast 6 is provided with the spring actuated pawl 12 connected by rod 13 with an operating lever as in the other forms and the toothed segment is provided with stop lugs 37 and 120 38 to limit the relative movement of the mast and toothed segment. A spring 39 affixed about the pivot 8 and having its cross portion 40 bearing on the segment 36 and its ends 41 bearing against the mast serves the 125 same function as the spring in Figs. 3 and 4 previously described. The front portion of the toothed segment has a forwardly and upwardly extending lip or the like 42 adapted to engage the under side of the 130

spring 20 and put the same under increased tension when the mast 6 is moved to the rear, the result being the same as in the operation of the parts shown in Figs. 3 and 4. 5 It will be noted that in this form of embodiment of the invention the rear end of the spring 20 is attached directly to the mast, as seen at 43 in Fig. 5, and the lip 42 is offset, as at 44, so as to be brought into 10 proper position to engage the under side of the spring to put it under tension.

In some cases it may be desirable to omit the lip on the clevis, where the clevis is employed, and allow the projection on the 15 toothed segment to contact with the clevis for putting the spring 20 under tension, the result being the same as in the different forms of construction hereinbefore specifically described.

20 From the above it will be seen that I have devised a simplified and cheaper form of construction than that illustrated in my prior patent hereinbefore referred to, and while the structural embodiments of the 25 invention as herein disclosed are what I at the present time consider preferable, it is evident that the same is subject to changes, variations and modifications in detail, proportion of parts etc., without departing 30 from the spirit of the invention or sacrificing any of its advantages. I, therefore, do not intend to restrict myself to the exact construction hereinbefore disclosed, but reserve the right to make such changes, variations and modifications in detail as come 35 properly within the scope of the protection prayed.

What is claimed as new is:—

1. In a wheeled implement, a spring-controlled mast pivotally mounted above the 40 axle thereof, a toothed segment pivotally mounted on the pivot of the mast, and means carried by the mast coöperable with said segment to hold the mast and segment in adjusted relation, said segment constructed to put the spring under tension.

2. In a wheeled implement, a spring controlled mast pivotally mounted above the axle, a segment pivotally mounted on the 50 pivot of the mast for movement independent of said mast, and means carried by the mast coöperable with said segment to hold the mast and segment in adjusted relation, and means movable with the segment to put the 55 spring under tension.

3. In a wheeled implement, a mast pivotally mounted above the axle, a spring acting thereon to move it in one direction, a pivotally mounted member movable with the 60 mast, means carried by the mast coöperable with said member to hold the mast and member in adjusted relation, said member adapted to apply tension directly to the under side of said spring when the mast is 65 moved.

4. In a wheeled implement, a spring controlled mast pivotally mounted above the axle, a toothed segment pivotally mounted on the pivot of the mast for movement by and also independent of the mast, means 70 carried by the mast coöperable with said segment to cause the mast and segment to move together, and means whereby the segment is moved on its pivot when said mast and segment are disconnected. 75

5. In a wheeled implement, a mast pivotally mounted above the axle, a spring acting on the mast, a toothed segment pivotally mounted for movement by and independent of the mast, means for holding said 80 segment for movement with the mast, and means movable with the mast and engageable beneath the spring to put the same under tension.

6. In a wheeled implement, a mast pivotally mounted above the axle a spring acting on the mast a toothed segment pivotally mounted for movement independent of the mast means for holding said segment for movement with the mast, a second spring 90 for moving said toothed segment in one direction when disconnected from the mast, and means movable with the mast and engageable beneath the first-named spring to put the same under tension. 95

7. In a wheeled implement, a pivotally mounted mast, a toothed segment mounted on the pivot of the mast for movement therewith, or independently thereof, a spring acting on the mast, a clevis pivotally connected 100 with the mast, and means movable with the clevis to apply pressure directly beneath the spring.

8. In a wheeled implement, a pivotally mounted mast, a spring acting thereon, a 105 toothed segment mounted on the pivot of the mast, for movement therewith a clevis pivotally mounted on the mast and having a projecting lip for direct engagement with said spring, and means on the segment for 110 engagement with said lip.

9. In a wheeled implement, a pivotally mounted mast, a spring acting thereon, a toothed segment mounted on the pivot of the mast, for movement therewith a clevis 115 pivotally mounted on the mast and having a projecting lip for direct engagement with said spring, and means on the segment for engagement with said lip, said lip having a convex upper face. 120

10. In a wheeled implement, a pivoted axle, a mast pivotally mounted above the pivot of the axle, a spring acting on said mast, a pivotally mounted toothed segment adapted to put said spring under tension, 125 and means carried by the mast coöperable with said segment to hold the mast and segment in adjusted relation.

11. In a wheeled implement, a pivoted axle, a mast pivotally mounted above the 130

pivot of the axle in substantial vertical alinement therewith, a spring acting on the mast, a toothed segment pivotally mounted on the pivot of the mast for movement independent of the latter, and means adapted to directly put said spring under tension when the mast is moved.

12. In a wheeled implement, a pivoted axle, a mast pivotally mounted above the pivot of the axle with the pivots of the axle and mast in substantial vertical alinement with each other, a spring acting on said mast to move it in one direction, and a pivotally mounted member movable by and with the mast to put the spring under tension when the mast is moved.

13. In a wheeled implement, a pivoted axle, a mast pivotally mounted above the pivot of the axle with the pivots of said axle and mast substantially in vertical alinement, a spring acting on the mast to move it in one direction, a pivotally mounted member movable by and with the mast, and means movable with said member to apply tension directly to the under side of said spring when the mast is moved.

14. In a wheeled implement, a pivoted axle, a mast pivotally mounted above the pivot of the axle with the pivots of the mast

and axle in substantial vertical alinement, a spring acting on the mast to move it in one direction, a toothed segment pivotally mounted for movement with and independent of the mast, means for causing the mast and segment to move together, and means for moving the segment on its pivot when said mast and segment are disconnected.

15. In a wheeled implement, a pivoted axle, a mast pivotally mounted above the pivot of the axle with the pivots of the mast and axle in substantial vertical alinement, a spring acting on the mast to move it in one direction, a toothed segment pivotally mounted for movement with and independent of the mast, means on the mast coöperable with the segment for moving said mast and segment together, means movable with the mast and engageable beneath the spring to put the same under tension, and a spring acting on said segment to actuate it when the mast and segment are disconnected.

Signed by me at Washington, D. C., this 19th day of February, 1914.

HENRY PETERSEN.
